(57) **CLAIM**

The ornamental design for a user interface for computer display, as shown and described.

DESCRIPTION

FIG. 1 is a front view of a user interface for computer display showing my new design;
FIG. 2 is a front view of a second embodiment thereof; and,
FIG. 3 is a front view of a third embodiment thereof.
The broken line drawing of the computer display, windows, and various graphical representations in all views is for illustrative purposes only and forms no part of the claimed design.

1 Claim, 3 Drawing Sheets

FIG. 1

FIG. 2

FIG. 3
